UNITED STATES PATENT OFFICE.

WILLIAM LANYON, OF ST. LOUIS, MISSOURI.

PROCESS IN THE ROASTING, CALCINING, DECARBONIZATION, AND DESULPHURIZATION OF CARBONATES, SULPHIDE ORES, AND OTHER MATERIALS, AND APPARATUS THEREFOR.

Application filed October 31, 1921. Serial No. 511,690.

To all whom it may concern:

Be it known that I, WILLIAM LANYON, a citizen of the United States, and resident of the city of St. Louis and State of Missouri, have invented certain new and useful Improvements in Processes in the Roasting, Calcining, Decarbonization, and Desulphurization of Carbonates, Sulphide Ores, and Other Materials, and Apparatus Therefor, of which the following is a specification containing a full, clear, and exact description, reference being had to the accompanying drawings, forming a part hereof.

My invention relates to certain new and useful process in the roasting, calcining, decarbonization and desulphurization of carbonates, sulphide ores and other materials, and apparatus therefor, and has for its primary object the subjection of ore or the other materials directly to highly heated air as either the sole or preponderating source of heat, to fully and efficiently perform the operation. My invention is especially designed for the desulphurization of ores, and particularly zinc sulphide ores.

My invention further consists of certain improvements in the apparatus in connection with the revolving or rotary furnace hereinafter referred to, and illustrated in the drawing, Fig. 1, and used in connection with the operation of the method or process above referred to.

In carrying out my process it may be applied to any of the well known types of roasting furnaces now known to the art, with more or less advantage in the results, but I deem it to be especially applicable to the revolving, or rotary type of furnace.

The illustrations disclose two types of furnace by means of which my process may be carried out, Fig. 1 being the rotary type and Figs. 2 and 3 being what is denominated in the art of zinc metallurgy as a multiple hearth zinc-ore roasting furnace.

Fig. 1 is a longitudinal sectional view of a rotary type of furnace; and Figs. 2 and 3 are the multiple hearth type, in which Fig. 2 is a section taken on the line 2—2 of Fig. 3, and Fig. 3 is taken on the line 3—3 of Fig. 2.

Referring to the drawings:

4 indicates the roasting drum preferably

circular in cross section, which has a lining of refractory material 5. The drum 4 is 55 provided with rings 6, which rest on supporting rollers 7, for holding the drum in the proper position.

Mounted on the drum 4 is the gear wheel 8, meshing with the pinion 9 driven by a 60 motor or other suitable source of power, 10.

By means of this construction the drum 4 may be rotated as desired. The drum 4 is provided with a plurality of openings 11 for drawing out samples of the ore at any 65 desired intervals of time or place, also for the purpose of taking the temperature within the furnace, also for the introduction of air at any desired temperature, and measuring the pressure of the gases within the 70 drum.

In the illustration (Fig. 1), 12 indicates the supply or receiving end, and 13 the discharge end, the ore or other material being fed into the roasting drum by means 75 of the hopper and conducting pipe 14. The supply or receiving end 12 is provided with a beveled inwardly projecting shoulder 15 for preventing the material under treatment from being discharged from the receiving end of the furnace. This shoulder has another function, which will be hereinafter described.

16 indicates the air heater, which may be made of any suitable construction, and 85 may be of the continuous counter current type or in duplicate or triplicate alternating hot air stove type, and is provided with an outlet into the superheated air chamber 17, into which the discharge end 90 13 of the drum projects. 18 indicates the air heating chamber in which are located air coils 19, or other means of heating the air. As the process or manner of heating air to a high temperature is so well known, 95 and is not made a matter of claim in this invention I deem it not necessary to go into a detailed description of such apparatus there being innumerable styles and types of such furnaces in operation in metallurgical works.

The cold air, atmosphere, is fed into the hot air ducts in the air heater by means of a blower 20. The air ducts in the air heater may be heated by any suitable fuel, 100 coal, gas, oil, etc., being burnt in the space

surrounding the air ducts. In practice in the desulphurization of ores, and to achieve my object, it is necessary to supply the heated air to the roasting chambers to at least a temperature of 1150 degrees Fahrenheit, and usually and chiefly a much higher than that temperature is required. In practice the air heated to the temperature required to suit the material under treatment in the furnace in the drum is discharged into the drum 4 from the air chamber 17, uniformly and under perfect mechanical control, preferably at a pressure in excess of atmosphere, which pressure may be attained at will through the use of the blower 20 supplying the air, and the curtailed outlet created by the shoulder 15, before referred to. The chamber 21 is designed to receive the exit gases from material under treatment in drum 4, and any dust contained therein, which dust will largely settle to the floor of the chamber 21, from which it may be removed through clean-out door 22. Connecting with the chamber 21 is a chimney flue 23, which takes away the exit gases and fumes from drum 4. The flue 23 is provided with a damper 24 for the purpose of further controlling the rate of exit of the gases from drum 4. 25 indicates the discharge chute through which the finished product passes. Said chute is provided with the gate 26 for controlling the letting out of the burnt product and closing the chamber 17 from the outside air.

In Figs. 2 and 3 I have shown a multiple hearth type of reverberatory ore roasting furnace used for the desulphurizing of zinc sulphide ores, which consists of the roasting furnace 27, and the hot air stove or air heating furnace 28, the two being connected together by means of the passage flue 29, opening into the highly heated air chamber 30. This chamber is provided in its side walls with openings 31 and 32, from which the heated air passes into and over the hearths or floors 33 on which the ore is resting. It will be noted in this connection that the openings 31 are larger than the openings 32, the idea being that in practice the greater amount and perhaps all of the heated air will preferably be admitted through openings 31, and the openings 32 are provided only for use at discretion, as the character of ore and heat of the furnace may require, said openings 32 being controllable to any degree of opening, or to closing of them off entirely through the door openings 37, opposite to openings 32. Above the air chamber 30 is the waste gas flue 34, receiving the waste gases from the top ore hearths through openings 35, and conducting them thence to chimney-flue 36. In flue 35 is a damper shown as 36, for regulating the outlet of the furnace, and passage of air and gases through the fur-

nace. This damper may be differently located or of a different style, any commonplace damper method will achieve the object.

The side walls of the roasting chamber 70 or furnace 27 are provided with openings 37 for the introduction of rakes and scrapers for stirring and moving the ore about, and for shifting the charges of ore from hearth to hearth, in the customary manner. By 75 the time the roast is completed it is on the lowermost hearth and is then removed from the furnace by raking it down through the passages 38 which lead to any suitable storage compartment. 80

In carrying out my process or method, particularly with relation to desulphurizing of ores, in both types of furnace shown, or other types commonly used in the art that portion of the ore under treatment 85 which possesses the least combustible qualities is subjected to the air most highly heated, direct from the air heater.

As the air progresses through the furnace it comes in contact with ore containing gradually increasing combustible and heat producing qualities, which tend decidedly to maintain the original temperature and produce a comparatively uniform and proper temperature continuously throughout 95 the entire furnace. As previously referred to, the characteristic feature of my process is the use of highly heated air, preferably solely, but at least in a measure to constitute the major or preponderating heat 100 agency; as the oxidizing agent, particularly in the desulphurizing of sulphide ores, particularly zinc sulphide ores. In case the resultant gases are to be used for the manufacture of sulphuric acid, or other sulphurous or sulphuric uses, it is requisite that 105 none of the oxides of carbon be present in them. Again in cases where the sulphur gases are not to be utilized, but wasted, it is desirable if possible to exclude all fuel 110 gases from contact with the ore under treatment, as it is well known that the carbon and hydrogen in them under heat and contact with the metal oxides tends to burn up or volatilize some of the metal values, which are thereby lost to the outside atmosphere, whereas in an atmosphere of pure air volatilization seldom occurs, and only at such extremely high temperatures as never or seldom, and then not necessarily 115 attained. 120

Regardless of which type of furnace is employed in carrying out my process, the ore is subjected to an atmosphere, preferably of highly heated air only, or an atmosphere highly heated in which the majority or preponderance of heat is supplied by highly heated air, and while I do not deem it as obligatory, (as fair to good results may be had at atmospheric pres- 130

sure) I consider it as helpful and beneficial to use the highly heated atmosphere under pressure, in that it causes the heated air to more thoroughly permeate the ore body and assist in its quicker oxidation, and also as preventing any inrush of cold air from without the furnace, through any door or other openings in the furnace structure, thus preserving the heat and protecting it from being diminished by chilling air currents from without, and furthermore, in the rotary type of furnace I am enabled to maintain a back pressure throughout the entire roasting chamber without the loss of any sulphur dioxide gases.

I have discovered that the rotary type, as described, of furnace is probably the most suitable for carrying out my process, because the material under treatment can be kept continually and uniformly moved about and agitated by the revolving of the drum 4, and thus slowly or quickly but unceasingly presenting fresh particles of the material under treatment to the action of the heat and the oxygen in the highly heated air, and at the same time advancing by gravity the material under treatment from the feed to the discharge end of the furnace. The advantages of my process may be briefly summarized as follows: The saving of fuel, owing to the making possible to a greater degree than customary the utilization of the fuel value of the sulphur contained in sulphide ores for their own combustion; the saving of time in the operation thus increasing capacity of plant installation; a more thorough, complete and satisfactory quality of the roast, and more easily attained; in the case of the rotary furnace referred to much saving in fuel and labor over any other style or type; supplies the maximum heat in shape of highly heated air where most needed and a substantially uniform heat throughout the roasting furnace; in the case of the rotary furnace referred to much less first cost of installation compared with other types, particularly the multiple hearth, fire-flue-heated-by-conduction types, mostly in use in producing sulphur gases for the manufacture of sulphuric acid, and furthermore, the possibility of maintaining a back pressure throughout the entire roasting chamber without the loss of any sulphur dioxide gases.

It is obvious that by means of the fan blower 20, and the damper 24, that I can control the volume of highly heated air that is passed through the roasting drum and I can also control the pressure of the highly heated air within said roasting drum by increasing or decreasing the speed of the blower. Furthermore, I can regulate the intensity of the highly heated air within said chamber in case of overheating by means of the openings or pockets 11. This

being accomplished by stopping the rotation of the drum while the openings are above the ore level, decreasing the speed of the fan blower, and injecting air through said openings or pockets. The temperature of the air may be further controlled by the speed with which it is forced through the hot air furnace by the fan blower, and the temperature of the hot air furnace.

It will be further observed that when the drum rotates, the entire mass of ore or material under treatment is always presenting a new or fresh surface for the direct action of the highly heated air,—this being in addition to the air which penetrates (due partly to pressure within the drum) between the particles of ore, and I am thus enabled to roast much larger particles of ore than where hand or mechanical stirring is employed, and the roasting is done more uniformly, thoroughly, and quickly.

Heretofore it has been the practice in the art of roasting and desulphurization of ores and like materials where high temperatures are required, to supply exteriorly or extraneously produced heat to perform the operation which has been accomplished in two ways: The first and oldest, where it is not required to preserve the sulphur or other gases from the material under treatment for further use, was by the introduction of fire gases and combustion of the same in the same chamber containing the ore or other material being treated. The other way was accomplished in what are denominated "muffle furnaces" in which the required heating medium to perform the operation is supplied by conduction and radiation of heat through brick walls or arches from fire flues or chambers adjoining the chambers or spaces occupied by the ore under treatment and in some cases in addition, in these so-called muffle furnaces a small amount of weakly heated air was used by introducing it into the ore chambers. But in all such cases this weakly heated air was negligible as to the matter of supplying the requisite quantity and temperature of air and heat—such furnaces being dependent practically entirely on the fire flues referred to for the chief or main source of heat to perform the operation.

In all such combined "muffle heated furnaces," if the fire flues or chambers were eliminated, they would fail and be unfit for the roasting and desulphurization of ores.

Furthermore, previous to my improvement wherein the rotary furnaces were employed, all of them show the use of fire gases introduced in the ore chamber or fire flues surrounding the ore chamber and for the sole purpose of applying the required heat medium for the operation.

According to my improvement in the method of roasting and desulphurization of

ores and like material, I eliminate and make unnecessary the muffle flues or other awkward and expensive ways of supplying the required heating medium and also eliminate the admission of fire gases in the same chamber with the ore gases.

Having fully described my invention, what I claim is:

1. The process of treating ores and the like, which consists in subjecting them in a furnace to the direct action of highly heated air regulated as to volume and intensity of temperature as the sole heating agent supplied and at the same time constantly exposing a fresh surface to said air.

2. The process of treating ores and the like, which consists in subjecting them in a furnace to the direct action of highly heated air regulated as to volume, temperature, and pressure as the sole heating agent supplied and at the same time constantly exposing a fresh surface to said air.

3. The process of treating ores and the like in a furnace which consists in subjecting the ore mass while under a continuous stream-like movement having a constantly changing surface directly to highly heated air regulated as to volume, intensity of temperature and pressure as the sole heating agent supplied.

4. The process of desulphurizing ores and the like in a furnace, which consists in subjecting the material while the mass thereof is in motion to highly heated air regulated as to initial temperature, volume, and pressure as the sole initial heating, and ignition agent supplied, the material having the least combustible value being subjected to the air having the highest temperature, the temperature of the air and gases in the furnace being thus maintained substantially uniform by the increasing combustibility of the moving mass of material under treatment.

5. In a desulphurizing furnace for ores, a rotating roasting chamber provided with a restricted inlet and a refractory lining, means for feeding a stream of ore into the restricted end of the chamber, radially arranged pockets carried by the chamber and provided with closures, said pockets adapted to receive a portion of the ore for sampling purposes, means for feeding highly heated air and regulating the volume thereof into the discharge end of the chamber, and means for regulating the pressure of the highly heated air within the roasting chamber.

6. In a furnace for the desulphurization of ores and the like, an unobstructed rotating drum lined with a refractory material having a tapered restricted receiving and a discharge end, a chamber adjacent to and communicating with the discharge end for producing and supplying to said drum a

heating agent composed of highly heated air, of sufficient volume and intensity of heat to produce and maintain combustion of the combustible in the ore in the drum as the sole heating agent supplied in the operation, a chamber for receiving and passing along the waste gases connected to and communicating with the receiving end, and means for feeding the ore in a stream into the receiving end of the drum.

7. In a furnace for the desulphurization of ores and the like, an unobstructed inclined rotating drum lined with a refractory material having a receiving and a discharge end, a chamber adjacent to and communicating with the discharge end for receiving and supplying a heating agent composed of highly heated air of a sufficient volume and intensity of heat to produce and maintain combustion of the combustible in the ore in the drum as the sole heating agent supplied in the operation, means for supplying highly heated air free from firing gases to said chamber, a chamber for receiving and passing along the waste gases connected to and communicating with the ore feeding or receiving end, and means for regulating the escape of waste gases, whereby the pressure of the highly heated air within the drum is regulated.

8. The process of treating ores and the like, which consists in subjecting them in a furnace while the mass is under continuous movement to the direct action of highly heated air of sufficient pressure to permeate the mass, as the sole ignition agent.

9. The process of treating ores and the like as a continuous operation, which consists in feeding the ore in stream like formation into a regulated blast of highly heated air of sufficient intensity of heat to produce ignition, and of sufficient volume to maintain combustion, and of sufficient pressure to permeate the ore under treatment.

10. The process of desulphurizing a mass of ore as a continuous operation, which consists in imparting to the mass a continuous movement and subjecting it during such movement to a blast of highly heated air of sufficient intensity of heat and volume to produce ignition and maintain combustion, and of sufficient pressure to permeate the mass being treated, whereby a uniform and thorough roast is quickly obtained.

11. The process of desulphurizing a mass of ore as a continuous operation, which consists in imparting to the mass a continuous stream-like movement having an ever changing surface and subjecting it during said movement to a supply of highly heated air of sufficient intensity of heat to produce ignition and volume to maintain combustion.

12. In a furnace, a rotating roasting chamber provided with radially extending

longitudinally arranged pockets communicating with the interior of the chamber, for the purpose of taking out samples of the material under treatment therein, for taking the temperature thereof, and injecting such air supplies that might be desirable, and closure means for said pockets spaced apart from the exterior surface of the chamber.

13. In a furnace, a rotating roasting chamber provided with radially arranged pockets for the purpose of taking out samples of the materials under treatment therein, for taking the temperature thereof, and injecting such air supplies that might be desirable, and means for opening and closing said pockets.

14. In a rotating reverberatory furnace, comprising an unobstructed rotating drum, lined with refractory material, having a receiving and discharge end, a hot air furnace, a chamber adjacent to and communicating with the discharge end connected to said furnace, for receiving and supplying to said drum a heating agent composed of highly heated air, of sufficient volume and intensity of heat to produce and maintain combustion of the combustible in the ore in the drum, as the sole heating agent supplied for the operation, a chamber for receiving and passing along of the waste gases connected to and communicating with the ore feeding or receiving end, a hopper and pipe connection leading into the receiving end of the drum, said drum having a plurality of longitudinally spaced apart radial pockets formed in or on its periphery, said pockets being for the purpose of taking samples of ore at various points throughout the length of the drum, also for taking the temperature within the drum, and for the introduction of air when and where required, means for opening and closing said pockets, and a valve controlled means for the roasted product located in the hot air receiving chamber for receiving and discharging the roasted product.

15. The process of desulphurizing a mass of ore as a continuous operation, which consists in imparting to the mass a continuous movement and subjecting it during said movement to a blast of highly heated air under pressure of sufficient intensity of heat and volume to produce ignition and maintain combustion.

16. The method of desulphurizing ores which consists in crushing the ore to the desired size; taking a mass of the crushed ore and imparting to it a continuous stream-like and sliding movement so as to produce and present continuously and in succession new surfaces on the mass of ore, and directly and simultaneously subjecting said surfaces to the action of an atmosphere composed of

highly heated air, or a preponderance thereof as the sole heating agent supplied for the operation.

17. The process of treating ores in a furnace which consists in permeating a portion of the mass of ore with highly heated air as the sole ignition agent while the mass is under continuous movement.

18. The process of treating ores in a furnace which consists in permeating a portion of the mass while under constant movement with air of sufficient intensity of temperature to cause ignition and sufficient volume to sustain combustion.

19. The process of treating ores which consists in supplying to a rotary furnace a constant supply of sulphide ore causing said ore to travel through said furnace in a stream-like manner having a constantly changing surface, and causing to pass through said furnace while said ore is in constant movement, a stream of air of sufficient intensity of temperature to cause ignition of the combustible in the ore and of sufficient volume to support combustion.

20. The process of treating ores which consists in supplying to a rotary furnace a constant supply of sulphide or other ore, causing said ore to travel through said furnace in a stream-like manner having a constantly changing surface, and causing to pass through said furnace in a direction opposite to the travel of said ore while said ore is in constant movement, a stream of air of sufficient intensity of temperature to cause ignition of the combustible in the ore and of sufficient volume to support combustion.

21. The process of treating ores and the like which consists in subjecting them in a furnace while the mass is under continuous movement to the direct action of a mobile supply of highly heated air as the sole ignition agent supplied and of sufficient volume to maintain combustion.

22. The process of desulphurizing a mass of sulphide ores which consists in taking a mass of sulphide ores and a volume of highly heated air of sufficient intensity of temperature to produce ignition and sufficient volume to maintain combustion, and partially confining the same in the presence of each other, imparting to the mass of ore a movement sufficient to produce a constantly changing mass surface and simultaneously imparting to the ore particles a movement sufficient to present the entire surface of said particles to said air, and simultaneously imparting to the volume of highly heated air a movement in a direction opposite to the movement of the ore mass.

In testimony whereof, I have signed my name to this specification.

WILLIAM LANYON.
